UNITED STATES PATENT OFFICE.

MAXMILIAN ERNST, OF CLEVELAND, OHIO.

DESIGN FOR A BOX-COVER.

SPECIFICATION forming part of Design No. 24,409, dated June 18, 1895.

Application filed May 13, 1895. Serial No. 549,189. Term of patent 7 years.

To all whom it may concern:

Be it known that I, MAXMILIAN ERNST, a citizen of the United States, residing at Cleveland, county of Cuyahoga, and State of Ohio, 5 have invented and produced a new and original Design for Box-Covers, of which the following is a specification, reference being had to the accompanying drawings, forming a part thereof.

10 Figure 1 is a picture of my newly-designed box-cover. Fig. 2 is a central vertical section of the cover applied to a box.

Referring to the drawings, *a* designates the box, and *b* the cover for the box.

15 The design consists in the peculiar configuration of the external surfaces of the box-cover. The box-cover is circular, or approximately circular, in plan and the upper convex

side or top thereof has the shape of the segment of a sphere, and the cover exteriorly, 20 both at the sides and top, has shallow irregular indentations, to form broken surfaces upon the cover externally, whereby the cover has the shape of a circular biscuit having a convex upper side and irregular outlines. 25

What I claim is—

The design for a box-cover herein shown and described.

In testimony whereof I sign this specification, in the presence of two witnesses, this 30 26th day of April, 1895.

MAXMILIAN ERNST.

Witnesses:

C. H. DORER,
L. WARD HOOVER.
